UNITED STATES PATENT OFFICE

WALTER J. BRUEHL, OF BUFFALO, NEW YORK

NECKTIE AND METHOD OF TYING SAME

Application filed May 24, 1929. Serial No. 365,695.

This invention relates to a necktie and the method of tying the same, the primary aim being to provide a novel manner of giving to the tie a four-in-hand appearance without subjecting the same to the wrinkling and wear and tear incidental to the tying of a four-in-hand knot.

In tying a four-in-hand knot the larger end portion of the tie is wrapped about the smaller end portion and then brought upwardly through the neck loop and threaded downwardly underneath one of the wrappings following which both ends are subjected to a tightening or tensioning in order to properly shape and position the tie. Constant tying and untying of this much desired and favored knot causes the tie quickly to become wrinkled and also subjects substantially the same portion of the tie to a constant wear and tear, causing the edges to fray and the adjacent portions to become soiled.

The present invention aims to provide a tie which, in all appearance, gives the four-in-hand dress to the tie without subjecting the tie to the usual wear and tear and the incidental wrinkle-forming manipulations of the well known four-in-hand tie.

The invention also resides in providing a core or body having the shape of a four-in-hand knot and over which is brought the larger end portion of the tie, rather than through it, and then completing the tie by means acting to conform the overlying end portion or flap to the underlying core or body so as to accord to the finished tie a four-in-hand appearance without, however, actually threading or passing the larger end portion through any restricted area which would tend to wrinkle or cause undue wear of the same.

A further object of the invention is to provide what might be termed an incomplete four-in-hand knot, leaving the larger end portion of the tie in overlying relation to the incomplete knot, utilizing the latter as a shaping core or body, conforming the overlying end portion to the core or body, and applying a conforming device about the tie so as to create an apparent line of demarcation between the knot portion and the free end portions of the tie; and the invention also has

for its object to provide means for bringing the lateral edges of the overlying tie flap rearwardly and beneath the core-forming knot to effect a snug embrace of the latter and impart a four-in-hand appearance to the tie.

55

In the drawing,

Fig. 1 indicates the completed tie incorporating the present invention.

Fig. 2 is a perspective view illustrating the incomplete four-in-hand knot with the larger end portion or flap ready to be positioned over the knot portion.

Fig. 3 is a view similar to Fig. 2 but showing the free flap portion overlying the core-forming knot.

Fig. 4 is a transverse section through Fig. 1, showing clearly the functioning of the clasp.

Fig. 5 is a view similar to Fig. 4 showing a modified form of clasp.

Referring more in detail to the accompanying drawing, the numeral 1 designates the smaller or minor end of the tie and the numeral 2 designates the larger or major end of the tie which, after being brought around the neck to form the neck loop 3, is then wrapped tightly one or more times about the smaller end portion 1 to form the incomplete four-in-hand knot 4 of a self-sustaining character to constitute a shaping core or body.

The usual four-in-hand knot is then completed by bringing the end 2 upwardly through the neck loop 3 and threading it downwardly beneath the outer wrapping of the knot 4. This causes the larger portion of the tie to be passed through the restricted passage, being exceedingly wrinkled therein, and the ends of the tie are then manipulated to tighten properly and position the tie about the wearer's neck. This causes the tie to become wrinkled, and when it is desired to untie the neckwear, considerable pulling of the tie about the knot is required in order to either slip the smaller end 1 from out of the knot 4 or to withdraw the larger end portion in a reverse series of steps to that followed in tying the knot. These several disadvantages I satisfactorily overcome, without sacrificing the favored knot appearance,

by my improved knot now to be described.

The incomplete knot, depicted in Fig. 2, provides a self-sustaining body or core having a somewhat triangular or inverted truncated appearance with a widened upper portion and a narrowed lower portion, characteristic of the four-in-hand tie knot. The knot 4 is shaped by the wrapping and positioning of the flap 2 as indicated in Fig. 2, and any further steps are primarily designed for securing the flap from unwrapping without destroying the knot. With the usual tying methods it has been impossible to preserve the knot except by inserting the larger end or flap 2 through the knot. By means of the present invention I am enabled to preserve the same neat appearance and shape of the four-in-hand tie without threading the larger end through the knot.

To this end the larger end portion or flap 2 is brought into overlying relation with the knot 4 as indicated in Fig. 3 so as to completely conceal and hide the core-forming or shaping knot 4 from which the flap 2 derives its four-in-hand knot appearance. Following the positioning of the flap 2 as indicated in Fig. 3 means are provided for conforming the tie flap to the underlying core, one form of a device for accomplishing this purpose being depicted in Fig. 4 wherein a clasp embodying a knot-embracing portion 5 has terminal arms 6 adapted to engage and conform the lateral portions of the flap 2 to the side and underlying portions of the core. In other words, the clasp 5 serves to shape the flap 2 about the core 4 by a more or less snug embrace whereby the flap 2 is given the same triangular or inverted truncated knot appearance as is found in the usual four-in-hand tie. The body portion 5 of the clasp, by encircling the tie at the base of the core 4, serves to define a line of demarcation between the apparent four-in-hand knot 7 and the depending flap 2. This serves to further retain the four-in-hand knot appearance. The clasp 5 may be provided with roughened portions 8 and 9 to hold the clasp against slipping downwardly on the tie and the lateral portions from slipping out from beneath the arms, or a pin 10 might be employed to secure the clasp from beneath to the tie.

This latter form of fastening means I have exemplified in Fig. 5, the clasp 5' being modified to a certain extent, being depicted as comprising a plurality of sections hinged together at 11 and having its arms 6' formed with apertures 6" to receive the pin 10, the pin being also passed through the lateral portions of the flap 2 as indicated.

By practicing the present invention it is possible to make an apparently complete four-in-hand knot without in reality completing the knot in accordance with the now prevailing practice. The knot 4 could be of a permanent structure if so desired, and whether permanent or temporary the knot

provides a substantial, shape-forming body or core to which the overlying flap is readily conformed by means of the flap-conforming device 5 (5'). It will be observed that the flap-conforming device causes the overlying flap 2 to lie smoothly about the knot 4, forming a more or less complete envelope for the knot so as to conceal the same from view, and that wrinkling of said flap is avoided because the flap is caused to lie smoothly over and about the core.

What is claimed is:

1. A method of tying a necktie to give a four-in-hand knot appearance, consisting in forming a neck loop having a minor end portion and a major end portion overlapping one another, wrapping the major end portion completely about the minor end portion in close embrace therewith and beneath the loop to form a substantial knot shaping core depending from the loop with a downward taper, then passing the free portion of the major end upwardly through the neck loop and thence draping it downwardly over the shaping core, then conforming the sides of the draped portion snugly about the shaping core whereby the overlying draped portion assumes the shape of the shaping core and conceals the same, and finally securing said sides behind the shaping core so as to hold said sides from view and maintain the snug conformability of the draped portion to the shaping core.

2. In combination with a four-in-hand necktie having a minor end portion and a major end portion overlapping one another to form a neck loop, the major end portion wrapped completely about the minor end portion in close embrace therewith and beneath the loop to form a substantial knot shaping core with a downward taper depending from the neck loop, the free flap of the major end portion passing upwardly through the loop and draping downwardly over the shaping core so as to conceal the same, of means for securing the sides of the flap snugly about the shaping core so as to conform the flap thereto for imparting to the draped flap the shape of the shaping core while at the same time completely concealing the same.

WALTER J. BRUEHL.
